UNITED STATES PATENT OFFICE.

ALEXANDER STEVENSON AND ARTHUR LOGAN, OF GLASGOW, SCOTLAND.

COAL-CUTTING MACHINE.

1,359,126.

Specification of Letters Patent. Patented Nov. 16, 1920.

Application filed November 13, 1919. Serial No. 337,845.

To all whom it may concern:

Be it known that we, ALEXANDER STEVENSON and ARTHUR LOGAN, both subjects of the King of the United Kingdom of Great Britain and Ireland, and residing at Glasgow, Scotland, have invented a certain new and useful Improvement in Coal-Cutting Machines, of which the following is a specification.

10 This invention relates to coal-cutting machines of the jib type.

The machine according to the invention may be regarded as a reconstruction of the machine known in the market as the "Sullivan" machine, being designed to adapt that machine to conditions met with in certain collieries.

In the reconstruction of the Sullivan machine a winch and wire rope have been substituted for the chain haulage of the Sullivan construction, provision being made for leading the rope directly to a point of anchorage or around a guide and thence in the reverse direction, whereby conveniently to effect the travel of the machine in either direction. The speed-reducing train between the motor and the barrel is simplified and provision is made for effecting conveniently variation of the rate of feed. Thus, 20 the speed reducing train of the present machine comprises simply a pair of spur gears, a pair of bevel gears, a crank and link and a pawl and ratchet mechanism associated with which latter is an adjustable mask.

30 In the accompanying drawings Figure 1 is a side elevation and Fig. 2 a plan showing diagrammatically so much of the machine as is necessary for the understanding of the invention.

40 Referring to the drawings, 1 denotes the rotor spindle or driving shaft fast on which is the spur pinion 2 meshing with a spur wheel 3 on a counter-shaft 4 that carries at its free end a bevel gear 5 meshing with a bevel gear 6 on a vertical shaft 7 rotatable in bearing members 8, 8'.

45 Fast on the upper end of the shaft 7 is a crank disk 9 to which is adjustably fitted a crank pin 10 connected by a link 11 to a rocking pawl-carrier 12 mounted on the

spindle 13 of the barrel or winding drum 14 and carrying a pawl 15 engageable with a ratchet wheel 16 fixed to rotate with the said barrel or drum 14. A spring-pressed detent 17 serves to prevent reverse rotation 55 of the ratchet wheel 16 and therewith of the barrel so as to prevent unwinding of the rope 18 from the barrel.

As will be understood, step by step rotary feeding movements are communicated to the 60 barrel from the rotor spindle or driving shaft 1 through the intermediary of the mechanism above described.

To vary the rate of feeding movement, there is centered on the spindle 13 an angularly adjustable plate 19 having at its edge a curved notch 19^a and being thus adapted according to its position of angular adjustment, to mask or shield more or less of the ratchet teeth and permit a shorter or longer 70 period of engagement of the ratchet wheel 16 by the pawl 15.

When the plate 19 is turned to such a position as to silence the pawl 15, or lift it out of engagement with the ratchet wheel 16, a 75 lug or tongue 20 on the plate 19 acts on the detent pawl 17 to disengage it from the ratchet wheel 16 so that the latter will be freed.

The plate 19 may be set in any desired 80 position of angular adjustment by means of a nut 21 on a screw-threaded spindle passing through a slot in said plate 19 and fitted into the post 22 on which the detent pawl 17 is pivoted. The post 22 passes 85 through a curved slot in the plate 19 which permits said plate to be adjusted to different working positions.

The rope 18 may be led from the barrel or drum 14 in the direction shown in full lines or it may be led reversely around either of two guide pulleys 23 as represented in dotted lines.

What we claim is:

A feeding mechanism for a coal-cutting 95 machine of the type referred to, comprising, in combination, a winding drum serving to receive a haulage rope, a driving shaft, a speed-reducing train between said driving shaft and said drum, said train in- 100

cluding a pair of spur gears, a pair of bevel gears, a crank and link, a pawl-carrier and pawl, a ratchet wheel rotating with said drum, an adjustable shield for the pawl, whereby the working throw of the latter may be varied, and means for holding said shield in different working positions.

5 In testimony whereof we have signed our

names to this specification in the presence of two subscribing witnesses.

ALEX. STEVENSON.
ARTHUR LOGAN.
